US0D1002364S

(12) **United States Design Patent** (10) Patent No.: **US D1,002,364 S**
(45) Date of Patent: ** Oct. 24, 2023

(54) **PACKAGING CONTAINER**

- (71) Applicant: **QUALTIA ALIMENTOS OPERACIONES, S. DE R.L. DE C.V.**, San Nicolás de los Garza (MX)
- (72) Inventors: **Bernardo Velázquez Navarro**, San Nicolás de los Garza (MX); **Ariel Esaul Gómez Martínez**, San Nicolás de los Garza (MX); **René Martínez Sierra**, San Nicolás de los Garza (MX)
- (73) Assignee: **QUALTIA ALIMENTOS OPERACIONES, S. DE R.L. DE C.V.**, San Nicolás de los Garza (MX)

(**) Term: **15 Years**

(21) Appl. No.: **29/836,709**

(22) Filed: **Apr. 28, 2022**

Related U.S. Application Data

(62) Division of application No. 29/737,156, filed on Jun. 5, 2020, now Pat. No. Des. 976,587.

(30) **Foreign Application Priority Data**

Dec. 5, 2019 (MX) MX/f/2019/003432
